US00D453179S

(12) **United States Design Patent** (10) Patent No.: **US D453,179 S**
 Neri et al. (45) Date of Patent: ** Jan. 29, 2002

(54) **PRINTER CASSETTE**

(75) Inventors: **Joel Neri**, Youngstown; **Susan Hammill**, West Seneca; **Jennifer Johnson**, Middleport; **Diane Kelly**, Cambria, all of NY (US); **John Krivda**, Ewing; **Karl Duerr**, Basking Ridge, both of NJ (US)

(73) Assignee: **IIMAK**, Amherst, NY (US)

(**) Term: **14 Years**

(21) Appl. No.: **29/127,041**

(22) Filed: **Jul. 27, 2000**

(51) LOC (7) Cl. **18-01**

(52) U.S. Cl. **D18/12**

(58) Field of Search **D18/12, 40, 56;**
D14/471, 481, 483, 484; 400/208, 234

(57) **CLAIM**

The ornamental design for a printer cassette, as shown.

DESCRIPTION

FIG. 1 is a top view of a printer cassette of our design; FIG. 2 is a front view of the printer cassette; FIG. 3 is a right side view of the printer cassette; FIG. 4 is a left side view of the printer cassette; FIG. 5 is a bottom view of the printer cassette; FIG. 6 is a perspective view of the printer cassette; and, FIG. 7 is a back view of the printer cassette. The broken lines shown in FIGS. 2 and 5-7 are for illustrative purposes only and form no part of the claimed design.

1 Claim, 6 Drawing Sheets
